UNITED STATES PATENT OFFICE.

WILLIAM M. SAUNDERS, OF WATERBURY, CONNECTICUT, ASSIGNOR TO THE HOGE MANUFACTURING COMPANY, INC., OF NEW YORK, N. Y., A CORPORATION OF NEW YORK.

DESIGN FOR A PROPEL PENCIL CAP.

Application filed October 18, 1921. Serial No. 508,629. Term of patent 14 years.

To all whom it may concern:

Be it known that I, WILLIAM M. SAUNDERS, a citizen of the United States, residing in the city of Waterbury, in the county of New Haven and State of Connecticut, have invented a new, original, and ornamental Design for a Propel Pencil Cap, of which the following is a specification, reference being had to the accompanying drawing, forming a part thereof.

The figure is a side elevation of a propel pencil cap applied to a pencil illustrated in dotted lines showing my new design.

I claim:

The ornamental design for a propel pencil cap as shown.

WILLIAM M. SAUNDERS.
